S. KUCHARSKI

OPTICAL PICTURE CABINET

Filed Oct. 1, 1919

UNITED STATES PATENT OFFICE.

STANISLAUS KUCHARSKI, OF CHARLOTTENBURG, NEAR BERLIN, GERMANY, AS
SIGNOR TO RICHARD A. HANSEMANN, OF BERLIN, GERMANY.

OPTICAL PICTURE CABINET.

Application filed October 1, 1919. Serial No. 327,828.

To all whom it may concern:

Be it known that I, STANISLAUS KUCHARSKI, engineer, a citizen of Germany, residing at and whose post-office address is Charlottenburg, near Berlin, Dernburgstrasse 45, Germany, have invented certain new and useful Improvements in Optical Picture Cabinets, of which the following is a specification.

10 This invention relates to a cabinet with a projecting or optical device arranged in its interior. The technical equipment of the known casings or boxes containing optical projecting apparatus renders them in-
15 adaptable for cabinets having the appear-
ance of furniture for the rooms of better
class dwellings or business establishments.
If the optical equipment is of the kind in
which the light beams pass from the lantern
20 to the screen and then back from the screen
to the spectators the casing has to have an
opening in the wall or side that is next to
the screen and the screen has to be elevated
in some way above the casing so that it
25 could only be folded back when the apparatus
is not in use (see for example German
Patent 263818). It is evident that it would
be difficult, if not impossible, to fashion a
contrivance of the kind in the shape of a
30 piece of decorative furniture.

Cases containing optical projecting de-
vices in which the beam passes from the lan-
tern to the screen and through the screen to
the spectators are also known. But to ren-
der the pictures projected onto the screen of
35 an apparatus of this kind observable to the
spectators the screen has to be arranged on
a horizontal line with the projecting lan-
tern in the wall of the casing opposite to the
40 lantern. Thus a long horizontal body en-
sues which is not suitable to be placed in
elegant dwellings or business establishments.

The present invention consists in an ar-
rangement of the mechanism of the enclosed
45 optical projecting equipment which enables
the enveloping cabinet to be made in any dec-
orative shape such as that of a tall cabi-
net, safe, etc., which is ready for a display of
50 pictures at all times without any opening or
closing of sides or walls. To accomplish
this the projecting lantern is arranged in the
lower part of the cabinet and so that it pro-
jects the beams or pictures onto an inclined

mirror situated in the upper part, a screen
being placed on a horizontal line with the
55 mirror in the opposite front wall of the
cabinet and the beams passing from the mir-
ror through this screen to the spectators.
By virtue of this combination it is not only
possible to let the screen permanently remain
60 in its position in its wall or side, as if it
were a fixed part of the piece of furniture
that the cabinet is designed to represent,
but the cabinet may also be kept in an up-
right position whilst displaying pictures and
65 so, if it is handsomely executed, it may be
placed anywhere as an ornamental safe or
the like.

A manner of carrying out the invention is
70 illustrated in the drawing which represents
a sectional side elevation of the optical pic-
ture cabinet. In the lower part of the cabi-
net *a*, which may be carried out in any style,
an optical lantern, for example, a cinematographic
75 apparatus *b* is arranged which, in the case illus-
trated, is mounted upon a floor *c* which moves on wheels and may be wheeled
out of the cabinet together with the lower
portion *d* of the cabinet front so as to make
it accessible for the insertion of a new pic-
ture band or film.

The projecting lantern throws its light
into the upper part of the cabinet and onto
an inclined mirror *e* in front of which a
screen *f* is inserted in the front cabinet
85 wall. The beams pass through the screen to
the spectators and the pictures displayed
thereon are observable in rooms illuminated
with daylight or artificial light. The screen
is bordered at the front with framework *g*
90 which may be executed in the style of a
proscenium. The screen *f* may be covered,
when the apparatus is not working, with a
curtain, picture, door or the like that is auto-
matically withdrawn when the motor of the
95 projecting apparatus is started.

In the illustration a music instrument *h*
is shewn in the cabinet. This instrument
may be a musical box or a gramophone
whose trumpet *i* emerges towards the ex-
terior of the cabinet, but is obscured from
100 the view of the spectators by suitable archi-
tectural ornaments or adapted to the style of
the surrounding furniture. An operative
relation is preferably established between
105 the automatic musical instrument and the

projecting apparatus or optical lantern by virtue of which the animated pictures move in synchronism with the music.

I claim:

- 5 An optical picture cabinet comprising a cabinet, an inclined mirror in the upper part of the cabinet with its reflecting surface on the under side, a screen in the front wall of the said cabinet and opposite to the
- 10 inclined mirror, a projecting peripheral border surrounding said screen, an optical lantern in the lower portion of the said cabinet adapted to project beams which are reflected by the said mirror onto the said screen, and

a removable wheeled platform carrying the 15 said optical lantern, said optical lantern being attached to the platform with its optical axis vertical and in such position thereon that when said platform is confined within the cabinet the projected picture will register substantially with said mirror.

20 In testimony whereof I have affixed my signature in presence of two witnesses.

STANISLAUS KUCHARSKI.
